UNITED STATES PATENT OFFICE.

WILLIAM EDWARD GOLLOGLY, OF INGHAM, QUEENSLAND, AUSTRALIA.

DEVICE FOR PREVENTING BACKFIRE IN THE CARBURETOR OR INLET PIPE OF INTERNAL-COMBUSTION ENGINES.

1,414,081.

Specification of Letters Patent. Patented Apr. 25, 1922.

Application filed May 12, 1921. Serial No. 468,968.

To all whom it may concern:

Be it known that I, WILLIAM EDWARD GOLLOGLY, a subject of the King of Great Britain and Ireland, residing at Francis 5 Street, Ingham, a post town in the division of North Queensland, State of Queensland, Commonwealth of Australia, have invented certain new and useful Improvements in a Device for Preventing Backfire in the Carburetor or Inlet Pipe of Internal-Combustion Engines, of which the following is a specification.

This invention relates to the prevention of fire in the induction pipe or carburetor of internal combustion engines in the event of the engine back-firing, and has for its object the provision of a simple and efficient means for preventing pre-ignited charges from blowing back or returning to the carburetor.

It is well known that pre-ignition of a gaseous charge, commonly known as a back-fire, is apt to cause the carburetor to take fire. The present invention aims at imprisoning the pre-ignited charge between the carburetor and the engine and delivering such charges either into the atmosphere or to the engine silencer, in a simple and efficient manner.

Referring to the drawings:

Figure 1. is a side elevation of the invention applied to the manifold of an internal combustion engine.

Figure 2. is a part sectional plan of Figure 1.

Figure 3. is a part sectional end elevation of Figure 2.

The invention is associated with an inlet or induction pipe 1. communicating at one end with a carburetor and secured at its other end to a chamber 2. having an inlet port 3 and a valve stem guide 4. around which is a valve seating 5. Resting upon the seating is the head 6 of a non-return valve having a stem 7 passing through the guide 4. Encircling the stem 7 is a coiled spring 8. one end of which bears against the guide 4 and the other end of which is retained by a nut 9.

Formed in the chamber 2 are opposite induction parts indicated at 10. Secured to the chamber 2 and communicating with the ports 10 are opposite induction branches 11. The branches 11 pass to the manifold 12 of the engine and are secured thereto by flanges or the like.

Formed in the chamber 2, adjacent the inlet port 3, is an escape port 13 having a valve seating 14 encircling a valve stem guide 15.

Resting upon the seating 14 is the head 16 of an escape valve having a stem 17 passing through the guide 15. Encircling the stem 17 is a coiled spring 18 one end of which bears against the guide 15 and the other end of which is retained by a nut 19. Secured to the chamber 2 by a flange or the like and passing from the port 13 is a delivery pipe 20. This may communicate with the engine silencer.

The cycle of operations with the invention is as follows:

Suction from the engine passes from the manifold 12 through the branches 11 to the chamber 2 and lifts the head 6 of the non-return valve from its seating 5, thereby compressing the spring 8. The fuel charge passes from the induction pipe (1), through the port 3 into the chamber 2, and along the induction branches 11 to the engine. The suction to the engine in conjunction with the spring 18 retains the head 16 of the escape valve firmly upon its seating 14. Upon a back-fire occurring, the non-return valve immediately closes under the influence of its spring 8, suction from the engine having ceased. The pre-ignited gases pass backwardly from the engine manifold 12, along the branches 11 into the chamber 2. Communication with the induction pipe 1 is prevented by the closed non-return valve. The escape valve, however, by the back pressure is opened and the head 16 moving from its seating 14 permits the pre-ignited charge to pass through the escape port into the delivery pipe 20. The pipe 20 may communicate direct with the atmosphere or with the engine silencer. Immediately suction by the engine is resumed, the escape valve closes with the assistance of its spring 18 and the non-return valve opens. Preferably the spring 18 is weaker than the spring 8 to permit of the non-return valve moving more rapidly than the escape valve.

It is to be particularly noted that the chamber 2 is here shown as a spherical member and that the valve parts controlling the inlet and outlet of the products are carried by and connected directly to this spherical member. Therefore, the improvement is readily usable as a unit, and can be readily

applied to existing structures the usual pipes now employed being simply cut and formed for connection with this unit which of course is otherwise complete.

5 Although the invention has been herein described, as applied to an internal combustion engine, it will be apparent to those skilled in the art that it may be applied with advantage to other elements or devices, such 10 as gas mains by providing a branch pipe or an enlargement in the main, and such adaptations are to be considered as within the scope of the invention.

What I claim is:—

15 A unit device for preventing back fire from an internal combustion engine, comprising a hollow spherical member having diametric openings communicating unobstructedly with the intake manifold, an 20 opening arranged between said diametric openings and communicating with the carburetor, a valve carried by said spherical

member for controlling the opening from the carburetor, said valve opening towards the spherical member and having a spring to 25 normally hold the valve in closed position, an exhaust pipe communicating with the member intermediate the manifold communications, a valve closing the exhaust pipe opening from the member, said valve opening towards the exhaust pipe and having a spring of less strength than the first mentioned spring to normally hold the valve closed, said valves and cooperating parts being carried wholly by said spherical hollow member, whereby the device is complete 35 as a unit for installation.

In testimony whereof, I have signed my name to this specification in the presence of two subscribing witnesses.

WILLIAM EDWARD GOLLOGLY.
